CARBURETOR

Filed Oct. 22, 1947

INVENTOR.
PAUL CALIXTE LACOSTE
BY

Paul Calixte Lacoste

Assignee, hereinafter referred to as the "assignee," is a French company, the name of which is "Société des Moteurs et de la Chambre de Commerce de l'Industrie de l'Automobile et de l'Aviation," and is located at 10, rue de l'Industrie, Paris, France. The assignee is the owner of the following registered trademark: "S.M.C.C. 10, rue de l'Industrie, Paris, France."

Patent and Trademark Office
U. S. Patent Office, Washington, D. C.

Paul Calixte Lacoste, Montrouge, France; Veuve Lestant, heiress of the estate of said Paul Calixte Lacoste, deceased, assignor to André Ader, Paris, France.

Application October 22, 1947, Serial No. 781,476
In France October 22, 1946

3 Claims. (Cl. 261—75)

1. My invention relates to a carburetor.

It is a well-known fact that since modern carburetors have been substituted for the old wick carburetors, no decided improvement has been accomplished in carburetors except for the use of the flooded jet producing a downward constant output flow.

Such arrangements have been completed by various auxiliary arrangements such as idling carburetors, recycling pumps and the like for improving to a certain extent the conditions of carburetion. But no essential modification has been brought to the formation of the mixture of air and fuel adapted to feed the engine cylinders.

As a matter of fact the droplets of fuel projected by the carburetor jet are collected in the form of liquid streamlets and the latter are urged against the collecting pipes and are not uniformly distributed inside the cylinders. The mixture is too rich in the first cylinder and too poor in the last, which leads to an excessive consumption of fuel and a rapid wear of the cylinders and pistons.

A carburetor according to the invention removes such drawbacks and submits the mixture of air and liquid fuel atomised in fine droplets at the output of the jet, to a suction movement directed perpendicularly to the normal suction axis and then to a movement of revolution inside a space specially provided for such purpose and out of which it is sucked and sent into the engine admission pipe.

The mixture thus obtained is not constituted by air admixed with atomised liquid fuel but by an intimate homogeneous mixture of air and vaporized fuel.

This invention is applicable either to a carburetor including an arrangement adapted to produce an efficient stirring of the mixture or else inside an auxiliary carburetor that is inserted in the path of the gases between the main carburetor and the engine.

Such an arrangement consists chiefly of a chamber the diameter of which is greater than that of a pipe admitting air or gases and opening into same. Inside said chamber are provided cylindrical or the like spaces adapted to form supplementary turbulency zones.

The fuel is fed by a spray nozzle or jet the slots of which are arranged in a manner such that the output may be provided in a transversal direction.

A better diffusion may be provided by projecting the carburetting fuel on to a heated tube of annular shape or by setting it into contact along

the walls of the carburetor with heated surfaces or again by setting it in contact with the surface of a porous body.

The accompanying drawing illustrates a form of execution of a carburetor according to my invention.

The carburetor is fed by a central jet or spray nozzle 6 including a cover 7 and slanting slots

10 for the output of the fuel. The fuel that is diffused fanwise is projected on to a hot pipe 9 inside the large chamber 15. It moves over the walls 10 of the chamber, flows through the turbulency zone 11 and finally sweeps over and saturates a porous body 12. The intimate mixture of air and carburetting fuel thus obtained is sucked into the admission pipe of the engine 13.

Obviously the scope of my invention is by no means restricted to the above disclosed particular form of execution of said invention. Numerous modifications may be obtained by modifying the size and shape of the apparatus; the zone of turbulency may be executed by means that are very different and the other arrangements disclosed are not essential, my invention being characterized primarily by the carburetor and the multiple applications thereof falling within the scope of accompanying claims and adapted to various possible requirements.

What I claim is:

- 30 1. In a carburetor, in combination, an admission tube for admitting an air-fuel mixture to the engine, the said admission tube having an end distant from the engine; a casing having side walls and a pair of opposite walls, forming a mixing chamber and being connected at one of said opposite walls to said end of said admission tube, said one of said opposite walls of said casing being formed with an aperture passing therethrough and in alignment with said admission tube, the said casing being of a substantially larger cross sectional area than said admission tube, whereby said side walls of said casing form a first extension of said admission tube which is of larger cross sectional area than said admission tube; a single baffle in said casing, said baffle being annular, forming a second extension of said admission tube and being of the same cross sectional area as said admission tube, the said baffle extending for a substantial distance into said casing and terminating in an end spaced from the other of said opposite walls of said casing, the space between said end of said baffle and said other opposite wall of said casing being substantially free and unobstructed; and
- 35 50 duct means having an open end portion in alignment with the said aperture and the said second extension of said admission tube.

- 55

ment with said admission tube, communicating with the interior of said casing and being connected to said other of said opposite walls of said casing for admitting an air-fuel mixture into said casing, whereby said air-fuel mixture will expand throughout said casing and be thoroughly mixed by said baffle before said mixture is drawn from about said baffle into said admission tube.

2. In a carburetor, in combination, an admission tube for admitting an air-fuel mixture to the engine, the said admission tube having an end distant from the engine; a casing having side walls and a pair of opposite walls, forming a mixing chamber and being connected at one of said opposite walls to said end of said admission tube, said one of said opposite walls of said casing being formed with an aperture passing therethrough and in alignment with said admission tube, the said casing being of a substantially larger cross sectional area than said admission tube, whereby said side walls of said casing form a first extension of said admission tube which is of larger cross sectional area than said admission tube; an annular baffle forming a second extension of said admission tube and being of the same cross sectional area as said admission tube, the said baffle extending approximately one-half of the distance from said one of said opposite walls of said casing to the other of said opposite walls of said casing; means for admitting air into said casing at said other of said opposite walls thereof; and means for spraying fuel against said side walls of said casing, whereby the air-fuel mixture will expand throughout said casing and be thoroughly mixed by said baffle before said mixture is drawn from about said baffle into said admission tube.

3. In a carburetor, in combination, an admission tube for admitting an air-fuel mixture to the engine, the said admission tube having an end distant from the engine; a substantially cylindrical casing having side walls and a pair of opposite walls, forming a mixing chamber and being concentrically connected at one of said opposite walls to said end of said admission tube, said one of said opposite walls of said casing

being formed with an aperture passing therethrough and in alignment with said admission tube, the said casing being of a substantially larger cross sectional area than said admission tube, whereby said side walls of said casing form a first extension of said admission tube which is of larger cross sectional area than said admission tube; a single baffle mounted in said casing, being annular, forming a second extension of said admission tube and being of the same cross sectional area as said admission tube, the said baffle extending approximately one half of the distance from one of said opposite walls of said casing to the other of said opposite walls of said casing and the other half of said distance being substantially free and unobstructed; means for admitting air into said casing at said other of said opposite walls thereof, said air admitting means being in alignment with said admission tube; and means for spraying fuel against said side walls of said casing, whereby the air-fuel mixture will expand throughout said casing and be thoroughly mixed by said baffle before said mixture is drawn from about said baffle into said admission tube.
